UNITED STATES PATENT OFFICE

JOSEPH N. VASEY, OF BROOKFIELD, ILLINOIS

MUSICAL INSTRUMENT

Application filed December 27, 1927. Serial No. 242,655.

My invention relates to musical instruments, such as pianos, and the object is to provide improved construction and arrangement of the string supporting frame and the 5 sounding body.

The general practice heretofore, in the construction of instruments such as pianos, has been to intimately secure the sounding body to the surrounding frame which supports 10 the pins for the strings extending across the sounding body. Such construction subjects the sounding body to the strains, stresses and distortions of the frame and prevents the sounding body from producing the proper 15 resonance, tone, volume and other characteristics.

One of the important objects of my invention is to provide arrangement which will make the sounding body independent of the 20 stresses, strains or distortions of the string supporting frame and leave it free to function properly and efficiently to exercise in tone, volume, resonance and other characteristics. With the exception of the string 25 pressure thereon the sounding body is entirely free of any pressures or strains either vertical or horizontal.

Another important object is to provide an improved and efficient sounding body entirely of non-metallic material such as wood 30 and of such form and construction that it will respond to the vibrations of the strings to produce maximum power, volume, and resonance of tone.

Another important object is to provide an efficient all metal yet comparatively light frame for surrounding and supporting the sounding body and for properly and rigidly holding the pins for tuning and stretching 40 the strings across the sounding body.

Referring to the drawing.

Fig. 1 is a plan view of the supporting frame and the sounding body thereon.

Fig. 2, is a sectional view on plane 2—2 of 45 Fig. 1, and

Fig. 3, is a sectional view on plane 3—3 of Fig. 1.

The supporting frame is preferably cast 50 integral of suitable metal such as cast iron or steel and comprises a rear wall structure 10,

and front wall structure 11, and the side walls 12 and 13. The rear wall structure is curved in accordance with the varying lengths of the strings which the frame is to support, and the wall structure is preferably of channeled 55 cross section as best shown in Fig. 2, to accommodate wooden blocks 14 for anchoring the tuning pins 15, the pins being extended thru holes 16 in the top wall of the wall structure and threading into the wooden blocks. 60 The blocks may be held in place by screws 17. The front ends of the strings are anchored to the stationary pins 18 secured to the front wall structure 11. To strengthen the supporting frame it may have one or more longitudinally extending brace members 19, and cross brace members 20, such brace members 65 preferably forming an integral part of the frame structure.

The sounding body is disposed within the four walls of the supporting frame but is supported solely by the ledges 21 and 22 extending inwardly from the front and rear wall structures of the supporting frame. The sounding body comprises the front and 70 rear end beams 23 and 24, preferably of wood, on top of which is secured the sounding board structure 25 and to the bottom of which beams are secured the sounding box structures *b* of which three are shown. 75 Each sounding box structure comprises a bottom wall 26 and side walls 27 secured to and extending between the end beams 23 and 24. Extending preferably along the median line in each sounding box is a stiffening brace 80 or rib 28 glued to the under side of the sounding board or panel and extending between the end beams 23 and 24. Each sounding box in its lower walls has preferably an opening 85 29 for the passage of sound.

The strings *S* extend over the top of the sounding body and rest on the rail 30 running along the rear edge of a bridge strip 31 which along its front edge is secured to the sounding board or panel 25, the strip being 90 in greater part spaced away from the panel. The pressure of the strings downwardly against the sounding body by way of the string rail 30 and strip 31 is the only force 95 holding the sounding body on the support- 100

ing ledges 21 and 22 of the supporting frame. The sounding body is entirely free from any other engagement with the supporting frame so that it will be uninfluenced by any strains, 5 stresses or distortions in or on the supporting frame. The sounding panel and the resounding boxes or chambers will therefore be entirely free and unhampered to receive the string vibration and to accord the proper 10 power, volume, and resonance to the tone. In other words the sounding body is entirely free to exercise its musical characteristics without being in any wise influenced by the 15 strings or other strain on the supporting frame. At the same time the supporting frame by its supporting contact with the sounding body will add resonance and power to the tone.

In practice a key board is mounted on and 20 supported entirely by the supporting frame independently of the sounding body. It is unnecessary to show such key board as its application is well known, its hammers responding to the striking of the keys to strike 25 and sound the corresponding strings.

The sounding body is of simple yet very 23 efficient construction. The end beams or bars 24 alone engage the supporting ledges 21 and 22, the sounding boxes or chambers 29 being clear at their ends of the ledges so that they may respond entirely independently and free of any contact with or influence by the supporting frame. The sounding board or 35 panel 25 is crowned slightly and as the pressure of the strings is transmitted thereto thru the rail strip 31 the panel will tend to flatten but will be prevented from so doing by the sounding boxes, the result being that the walls of said sounding boxes will be 40 tensioned and their efficiency to increase the sound volume and resonance will be greatly improved.

Having described my invention I claim as follows:

45 1. In a musical instrument, the combination of a string supporting frame, a sounding body surrounded by said frame, said frame having ledges on which said body is seated at its edges, said body being otherwise free from said frame, strings on said frame spanning said body, and bridge structure on said body engaged by the strings whereby said body is held by the pressure of the strings in position on said ledges.

55 2. In a musical instrument, the combination of a string supporting frame, a sounding body surrounded by said frame, said frame having ledges on its front and rear walls, said body resting on said ledges but being otherwise free of said frame, strings extending between the front and rear walls of said frame and across said body, and bridge structure on said body engaged by said string whereby said body is held by the string pressure in 60 65 position on said ledges.

3. In a musical instrument, the combination of a string supporting frame, a sounding body surrounded by said frame, said frame having ledges on its front and rear walls, said body resting at its front and rear edges on 70 said ledges and being otherwise entirely free of said frame, strings extending between the front and rear walls of said frame, and a string rail along the rear edge of said body engaged by said string, the pressure of said strings on said body holding it in place on 75 said ledges.

4. In a musical instrument, the combination of a string supporting frame cast integral of metal, a sounding body constructed entirely of wood, said supporting frame having ledges on its front and rear walls and said sounding body resting at its edges on 80 said ledges but being otherwise free from said frame, anchor pins on the front wall of said frame and tuning pins on the rear wall thereof, strings extending between said pins, and a bridge structure on said sounding body engaged by said strings whereby said body is held in place on said ledges by the string 85 pressure.

5. In a musical instrument, the combination of a sounding body of wood, a metallic string supporting frame surrounding said body, ledges on said frame, said body resting 95 on said ledges but being otherwise free from said frame, a string rail on said body engaged by said strings, said body being held to said ledges solely by the pressure of said strings, and a key board mounted on said 100 frame over said strings.

6. In a musical instrument, a sounding body comprising a sounding board, front and rear beams to which said board is secured, a bottom wall attached to the opposite face of said beams, and a plurality of sounding boxes disposed below said board and composed of said wall and partitions carried solely thereby.

7. In a musical instrument, a sounding body comprising front and rear supporting beams, a sounding panel secured at its front and rear to the top of said beams, a plurality of parallel sounding boxes extending between and secured against the underside of said beams, said sounding boxes being separated from each other and from said sounding panels.

8. In a piano structure, the combination of a sounding body of wood, a metallic string supporting frame surrounding said body, ledges on said frame, said body resting on said ledges and comprising a sounding panel and a plurality of sounding boxes below said panel, said sounding boxes being spaced from said panel and from said frame.

In witness whereof, I have hereunto subscribed my name this 22nd day of December, 1927.

JOSEPH N. VASEY. 130
